UNITED STATES PATENT OFFICE.

NEWTON H. TURNER, OF ROYERSFORD, PENNSYLVANIA.

LADDER.

1,162,000.

Specification of Letters Patent.

Patented Nov. 30, 1915.

Application filed April 27, 1915. Serial No. 24,288.

To all whom it may concern:

Be it known that I, NEWTON H. TURNER, a citizen of the United States, residing at Royersford, in the county of Montgomery and State of Pennsylvania, have invented 5 new and useful Improvements in Ladders, of which the following is a specification.

An object of the invention is to provide a ladder which will insure the person climbing the same against accidental tilting of the ladder; which can be used in the nature of a scaffold and which also is conveniently adapted for use in interior or exterior work and particularly useful in enabling persons 15 to remove fruit from the high portions of trees.

The invention comprehends, among other features, the provision of a ladder having a suitable base or stabilizing portion and 20 ladder sections upstanding therefrom, with the ladder sections adjustable with respect to the base so that the desired inclination can be obtained in order to prevent accidental tilting of the ladder sections when 25 a person climbs up the rungs thereof.

Still further objects of the invention reside in a ladder which can be quickly set up and as readily taken down and in which certain adjustments permit of placing the 30 ladder in operative position upon surfaces that are not entirely smooth or even.

In the further disclosure of the invention reference is to be had to the accompanying drawings, constituting a part of this specification, in which similar characters of reference denote corresponding parts in all the 35 views, and in which:

Figure 1 is a side elevation of the ladder showing the same in position for use and 40 also indicating the manner in which it can be used as a scaffold; Fig. 2 is an end view; Fig. 3 is another end view; Fig. 4 is a fragmentary vertical sectional view taken on the line 4—4 in Fig. 1; Fig. 5 is a sectional view 45 taken through the adjustable base.

Referring more particularly to the views, I employ a ladder body 10 preferably consisting of superposed connected ladder sections 11, the upper end of the lower ladder 50 section being provided with longitudinal slots 12 in which is adapted to be fitted the ends of a cross bar 13 upon the upper ladder section 11, with the lower ends of the upper ladder section provided with slots 14 fitting 55 into one of the rungs 15 of the lower ladder

section, a suitable handled nut 16 being threaded on the cross bar 13 whereby, when the nut is screwed up against the face of the lower ladder section, it will rigidly hold the upper ladder section in locked relation to the former. The lower end of the lower ladder section is provided with transverse slots 17 in which is received the cross piece 18 of a base 19 including upwardly inclined brace arms 20 and the lower ladder section 60 is provided with a cross bar 21 which constitutes one of the usual rungs 15, but has its ends projecting beyond the sides of the ladder sections. The upper ends of the bracing arms 20 are formed with eyes through 70 which the projecting ends of the cross bar 21 pass and transverse pins 23 pass through openings 24 in the projecting ends of the cross bar 21 to hold the eyes 22 of the arms 20 against accidental removal from the cross 75 bar.

A cross bar 25 similar to the cross bar 13 is arranged near the lower end of the lower ladder section and the prop section 26 is provided at each inner end with a cross 80 bayonet slot 27, through which the projecting ends of the cross bar 25 pass in order to secure the inner end of the prop section to the lower end of the lower ladder section a distance above the base. The prop section 85 26 is of substantially the same construction as the ladder sections 11 and, in fact, is a ladder section in itself, and it will be clearly apparent that when the base 19 is removed the prop section can be swung downwardly 90 into vertical alignment with the ladder sections 11 to form a continuous part thereof and provide the usual straight ladder. In the present instance, however, the prop section 26 is used as a means for insuring the 95 proper stability necessary in order that the ladder body can be climbed by a person, and to this end the prop section has one of its rungs 28 in the nature of a cross bar, with its ends projecting beyond the sides of the prop section and provided with openings 29 through which are adapted to pass suitable pins 30.

An adjustable brace 31 is provided and consists particularly of a screw 32 having 105 its inner end swiveled to a head 33 and provided with a handle 34, the other end of the screw being in threaded engagement with a head 35, the heads 33 and 35 being somewhat similar and each having a plurality of 110

arms 36 mounted to swing thereon, with the arms of each head relatively diverging and formed at their ends with eyes 37, the upper arms of the adjustable brace being adapted 5 to have the extremities of the cross bar 21 pass therethrough, with the lower arms having the extremities of the rung 28 passing through the eyes of the lower arms.

Now it will be clearly seen that there is provided 10 a connection between the ladder body and the prop section and which connection is effected a distance from the points of pivotal connection of the lower ladder section with the prop section. It will be further apparent 15 that by turning the handle 34 the inclination of the ladder body and the base supporting the same can be increased or decreased with respect to the prop section as desired, and with this character of structure it will be 20 clear that the ladder described may be used on an uneven ground even in instances where the free end of the prop section will be on a higher plane than the inner end thereof, the adjustable brace permitting of an inclination 25 of the ladder body toward the prop section in the latter instance and which inclination is sufficient to stabilize the entire structure when a person climbs up the ladder body, it being of course understood that the 30 connection between the upper arms of the brace and the ladder body and the lower arms of the brace and the prop section is one which permits of a swinging of the brace as it is adjusted by means of a screw 32. It 35 will also be apparent that the prop section can be arranged to extend to the left of the ladder body or to the right thereof as desired, this being particularly facilitated by the provision of the cross bayonet slots 27 in 40 the inner ends of the prop section and which prevent accidental slipping of the inner end of the prop section out of engagement with the cross bar at the lower end of the lower ladder section.

45 Having thus described my invention, I claim:

1. In a ladder, the combination with a ladder body and a prop section, a base, side arms on the base, a cross bar on the ladder 50 body and having the side arms of the base connected thereto, and an adjustable brace in swinging connection with the prop section and with the cross bar of the ladder body whereby the inclination of the ladder body

can be increased or decreased relatively to 55 said prop section.

2. In combination with a ladder body and a prop section therefor, a brace comprising an upper head, arms mounted to swing on the upper head and connecting with the ladder body, a lower head, arms mounted to swing on the lower head and connecting with the prop section, and a screw swiveled in the upper head and in threaded engagement with the lower head whereby said heads can be moved toward or away from each other to increase or decrease the inclination of said ladder body relatively to said prop section.

3. In combination with a ladder body and a prop section therefor, a brace comprising an upper head, arms mounted to swing on the upper head and connecting with the ladder body, a lower head, arms mounted to swing on the lower head and connecting with the prop section, a screw swiveled in the upper head and in threaded engagement with the lower head whereby said heads can be moved toward or away from each other to increase or decrease the inclination of said 80 ladder body relatively to said prop section, and a handle on one end of said screw for operating the same.

4. In combination with a ladder body and a prop section therefor, a brace comprising an upper head, arms mounted to swing on the upper head and connecting with the ladder body, a lower head, arms mounted to swing on the lower head and connecting with the prop section, a screw swiveled in the upper head and in threaded engagement with the lower head whereby said heads can be moved toward or away from each other to increase or decrease the inclination of said ladder body relatively to said prop section, a handle on one end of said screw for operating the same, a base supporting said ladder body, and side arms on said base and having connection with the ladder body at the point of connection of the arms of the upper head with the ladder body.

In testimony whereof I affix my signature in presence of two witnesses.

NEWTON H. TURNER.
